(57) **CLAIM**

The ornamental design for a LED recessed light apparatus, as shown and described.

DESCRIPTION

FIG. 1 is a bottom perspective view of a LED recessed light apparatus showing our design;

FIG. 2 is a top perspective view thereof;

FIG. 3 is a front side view thereof;

FIG. 4 is a back side view thereof;

FIG. 5 is another side view thereof;

FIG. 6 is an opposing side view thereof;

FIG. 7 is a top view thereof;

FIG. 8 is a bottom view thereof;

FIG. 9 is a bottom perspective environmental view showing the LED recessed light apparatus in a ceiling installation;

FIG. 10 is a bottom perspective view of another embodiment of the LED recessed light apparatus showing our design;

FIG. 11 is a top perspective view thereof;

FIG. 12 is a front side view thereof;

FIG. 13 is a back side view thereof;

FIG. 14 is another side view thereof;

FIG. 15 is an opposing side view thereof;

FIG. 16 is a top view thereof;

FIG. 17 is a bottom view thereof; and,

FIG. 18 is a bottom perspective environmental view showing the LED recessed light apparatus in a ceiling installation.

The broken lines shown herein are for illustrative purposes only and form no part of the claimed design. The illustrated device is not limited to the scale shown.
